UNITED STATES PATENT OFFICE

2,315,990

SAFETY RAZOR

Nicholas Testi, Boston, Mass., assignor to Gillette Safety Razor Company, Boston, Mass., a corporation of Delaware

Application September 10, 1940, Serial No. 356,173

20 Claims. (Cl. 30—40)

This invention consists in a new and improved safety razor characterized by blade-clamping members which are held together under spring pressure, so that a user is relieved of any necessity of tightening the razor after a blade has been presented thereto. The invention includes within its scope the novel combination of such a safety razor with a prying device for temporarily separating the blade-clamping members, and specifically the combination of such a safety razor with a blade magazine shaped to function as a prying device.

Many features of the invention lie in the structural characteristics of the safety razor, such as the shape of its one-piece cap, the structure and location of its spring-clamping means and the fulcrum provided for the prying device.

The magazine is complete in itself as a container for a supply of fresh blades and is equipped with blade-feeding means for separating one blade at a time from the supply and ejecting it from the magazine. It is, moreover, shaped to engage a fulcrum supplied in the razor and is movable about that fulcrum to engage and temporarily pry one blade-clamping member from the other, thus opening a passage between said members into which a blade from the magazine may be directly inserted.

As herein shown the fulcrum comprises a block arranged to swing upon one of the blade-clamping members and having a guideway to receive a part of the magazine, namely the bottom plate which is forked to make preliminary engagement with the fulcrum block and which may be thereupon swung with the fulcrum block into contact with the cap member of the razor. As the cap member is thus pried up the magazine encounters stops which arrest it at the proper point and align its delivery opening with the blade seat in the razor. After the magazine has made its preliminary engagement it may be shifted longitudinally in the fulcrum block to position the blade about to be delivered in proximity to the blade seat of the safety razor. The ejection of the blade from the magazine and its presentation to the blade seat of the safety razor is then effected reliably, accurately and without any danger of cutting the user.

These and other features of the invention will be best understood and appreciated from the following description of a preferred embodiment thereof, selected for purposes of illustration and shown in the accompanying drawings, in which:

Fig. 1 is a view of the razor in side elevation;

Fig. 2 is a corresponding view in longitudinal section;

Fig. 3 is a view in cross section on the line 3—3 of Fig. 1;

Fig. 4 is a view in cross section on the line 4—4 of Fig. 1;

Fig. 5 is a view in perspective of the fulcrum block shown on an enlarged scale;

Figs. 6 and 7 are views in perspective respectively of the spring and cover plate;

Fig. 8 is a view of the razor in side elevation showing the magazine in its position of initial engagement therewith, the magazine being shown in section;

Fig. 9 is a similar view showing the magazine swung into operative position;

Fig. 10 is a plan view corresponding to Fig. 9 except that the feeding device is shown in an advanced position, and

Fig. 11 is a fragmentary view in longitudinal section on the line 11—11 of Fig. 10 and on a still larger scale.

The safety razor illustrated includes in its structure a handle 10 which is screwed at its upper end into an elongated blade-supporting member or plate 11 forming one of two blade-clamping members between which a flexible double-edged blade 40 is maintained in a condition of transverse curvature for the shaving operation. The blade support 11 is shouldered to provide parallel fulcrum shoulders over which the blade is flexed, as best shown in Figs. 3 and 4. Its longitudinal edges are formed as guard bars 12 being deflected downwardly and outwardly and partially separated from the body of the support by longitudinal slots. The inner or blade-engaging face of the member 11 is provided at one end with a central longitudinal blade-locating rib 13 rounded at both ends so that a blade may be conveniently passed over it in being presented to or withdrawn from the razor. Beneath the blade-locating rib 13 the blade-supporting member is provided in its lower face with a longitudinal slot 14 and in the other end of the member a transverse slot 15 is also provided in which fits the upturned end flange of an elongated cover plate 16 shown separately in Fig. 7. The underlying cover plate has a perforation 17 shaped to surround freely the neck of the handle and the perforation is elongated to coincide or register substantially with the groove 14 already mentioned. Adjacent to the elongated part of the perforation is provided a pair of parallel downturned flanges 18 which act as stops and guides for a prying device to be described presently.

A pivoted fulcrum block 20 provided with transverse journals 21 is pivotally mounted to swing beneath the blade-supporting member 11, the journals 21 being received in a transverse channel in the lower face of the member 11 and being retained therein by the cover plate 16 as will appear from an inspection of Figs. 2 or 11. The fulcrum block is grooved or shouldered in its side faces to provide an undercut guideway 22 located adjacent and parallel to its outer face, that is to say, the face of the block which is lowermost when the safety razor is in upright position as shown in Figs. 1 and 2.

The safety razor of my invention is not limited to any specific type of replaceable razor blade but as herein shown is adapted to take a thin flexible double edged blade 40 having a central longitudinal slot in which the blade-locating rib 13 is designed to fit. The blade is provided with recesses at each corner which define elongated unsharpened end portions in the blade.

Co-operating with the blade-supporting member 11 is a cap member having an upper portion 26 with a concave blade-shaping face, downwardly extending arms 27 at one end and a lower inwardly extending plate 28 perforated to receive the upper end of the handle with clearance. The blade-clamping portion 26 of the cap is provided at one end in its inner face with a longitudinal slot to receive the blade-locating rib 13. The portion 26 of the cap is narrower than the blade-supporting member 11, extending just beyond the fulcrum shoulders thereof and it is slightly longer than the blade-supporting member so that its opposite corners furnish projecting faces to be engaged by the prying device already mentioned. At the rear or left end of the blade-supporting plate, as seen in the drawings, the guards 12 are extended outside the arms 27 and the cap member thereof is loosely connected to swing about one end of the member 11. A leaf-spring 24 is partially enclosed within the cap member and bears at its opposite forked ends against the under face of the member 11, being provided with a clearance hole 25 for the passage of the handle. The spring 24 therefore acts at all times to move the cap member downwardly and thus to hold the blade-engaging members 11 and 26 in yielding clamping engagement with sufficient pressure to bow the blade 40 transversely and cause it to assume shaving position.

The safety razor thus far described may be supplied with a blade by hand if desired and in this case the blade is merely pushed forcibly in an endwise direction into the right-hand end of the razor as seen in Figs. 1 and 2, while the spring-clamping pressure of the members 11 and 26 is relieved by pushing the bottom plate cap 28 upwardly by the fingers. Under these circumstances the inner end of the blade will pass up over the rib 13 and then the rib will enter the longitudinal slot of the blade, thereafter centralizing and guiding the blade as it is moved rearwardly until its advancing shoulders engage the arms 27 of the cap member. The blade is thus fully seated upon the convex blade-supporting member 11 and when the spring 24 is permitted to do so the concave cap portion 26 bows the blade and holds it firmly in shaving position as shown in Figs. 3 and 4. The right-hand end edge of the blade-shaping portion 26 of the cap is made concave as shown in Fig. 10 to facilitate the presentation and removal of a blade 40 by hand as just explained.

My invention, however, includes a novel 75 the uppermost blade 40 of the magazine is aligned

double-ended blade magazine which has the functions of a prying device to separate temporarily the blade-clamping members and of a mechanical blade-feeding device by which one blade at a time may be supplied to the safety razor without being touched by the user. The magazine herein shown corresponds in many respects to that forming the subject matter of my prior application Serial No. 331,847, filed April 26, 1940, although the magazine of that application is not, without modification, adapted to serve as a prying device.

The magazine herein shown has an elongated tubular body which includes a base 30, side walls and parallel overhanging flanges 31, separated from each other by a continuous central opening in the form of a wide slot. The magazine may be bent up and shaped out of metal or moulded of any suitable plastic compound. An elongated blade-locating bar or rib 32 is secured to the bottom of the magazine in symmetrical relation between the flanges 31. The bar is substantially shorter than the magazine and its ends are spaced equally within the ends of the magazine which are both open. In its upper edge it is provided with two deep notches having rounded corners and these notches set off solid end portions or blade stops. The blades 40 are retained in a stack upon the rib 32 in staggered relation, that is to say, certain blades are located so as to engage one end of the rib 32 and alternate blades are located with their end portions filling one of the notches in the rib 32. The result is that the blades overlap and that adjacent blades are separated from each other throughout both of their end portions.

The bottom 30 of the magazine is provided at each end with a centrally-disposed longitudinal slot 33 of such dimensions as to fit freely into the undercut guideway 22 of the fulcrum block 20 for substantially the whole length of the block. The flanges 31 are provided at each end in their inner corners with oblique upstanding ribs 34 which constitute stiff pressure-applying surfaces and also act as stops for a feed slide 36. The latter has undercut ways in its edges to receive the edges of the overhanging flanges 31 and is provided with a corrugated upper face. It extends into the magazine sufficiently to engage only the uppermost blade 40 in the stack. The bottom of the magazine is reinforced with a fibre seat 35 and between this and the lowermost blade in the stack are provided leaf springs 37 which hold the blade stack upwardly with the uppermost blade in contact with the flanges 31 of the magazine.

In using the magazine thus described with the safety razor herein shown the magazine is presented for initial engagement with the fulcrum block 20 as suggested in Fig. 8. This is effected by that end of the magazine which happens to be remote from the feeding slide 36, and while the fulcrum block 20 of the razor occupies its normal inclined position. In this position the forked end of the magazine may be slipped into the guideway of the fulcrum block. Having made this preliminary engagement the outer end of the magazine is swung upwardly into horizontal position as suggested in Fig. 9 and as determined by the flanges 18 of the cover plate already referred to. The flanges 18 are designed to arrest the movement of the magazine when it reaches a horizontal position, as shown in Fig. 9 or 11, and when so arrested the uppermost blade 40 of the magazine is aligned

with the blade-supporting face of the member 11. Meanwhile the fulcrum block has rocked upon its journals 21 and the flanges 31 have engaged the projecting corners of the cap 26 and rocked the right-hand end of the cap upwardly as shown in Figs. 9 and 11. This prying or separating movement of the blade-clamping members has provided free passage for the reception of the uppermost blade 40 in the stack. That blade, therefore, may now be advanced by moving the feed slide toward the left, thus picking the uppermost blade in the stack and advancing it into shaving position in the razor. As soon as the blade has been properly positioned, the magazine is allowed to swing back to its initial position and is disengaged from the fulcrum block 20, leaving the blade in position beneath the spring-pressed cap 26.

At the conclusion of the shaving operation, or when it is desired to remove the used blade, the user may grasp the outer end of the blade and withdraw it endwise toward the right from the razor. In supplying a new blade from the magazine the latter is reversed end-for-end since the feed slide has been left in a position adjacent to the razor. As newly presented, the other end of the magazine is engaged with the fulcrum block and the uppermost blade in the stack ejected by a movement of the feed slide toward the razor but in the opposite direction relatively to the magazine from that in which the previous blade delivery took place.

It will be appreciated that many details of construction may be varied from those herein illustrated, all within the scope of the invention. For example, while the invention has been illustrated as embodied in a safety razor shaped to flex the blade transversely it would be within the scope of the invention to utilize clamping members having flat blade-clamping faces for clamping the blade in a flat shaving condition. The shape and location of the spring for urging together the blade clamping members may also be widely varied from that shown and, of course, a stationary fulcrum may be employed instead of the pivotally mounted block selected herein.

Having thus disclosed my invention, but only in a single preferred form, I claim as new and desire to secure by Letters Patent:

1. A safety razor having an elongated blade-supporting member, a cooperating cap member having a concave blade-engaging face and being mounted thereon to swing about a transverse axis at one end of the blade-supporting member, and spring means at all times urging the two said members together with blade-clamping pressure.

2. A safety razor having an elongated blade-supporting member, a cooperating cap member mounted in the razor to swing about one end of the blade-supporting member as a fulcrum, blade-positioning means, and a spring for urging the free end of said cap member toward the blade-supporting member.

3. A safety razor having elongated blade-holding members connected together at one end and presenting a blade seat for the reception of a blade inserted endwise between them, and spring clamping means for said members acting to swing them into clamping relation.

4. A safety razor having elongated blade-clamping members loosely connected together at one end and presenting a blade seat for a blade inserted endwise between them, and spring means tending to close said members, one of

said members having a fulcrum and the other a pressure-receiving face for a prying device operating to separate them.

5. A safety razor having a handle, superposed blade-clamping members carried thereby and having a loose connection at one edge, a closing spring tending at all times to move said members together, a fulcrum member located below one member for supporting a prying device effective to separate the said blade-clamping members, and a pressure-receiving face on the other member to receive pressure of the prying device.

10 6. A safety razor having a handle, a stationary blade-supporting plate thereon, a box-like cap fitted about one end of said plate and extending on both sides thereof, a spring tending at all times to hold said cap in blade-clamping position and being partially enclosed by the cap, and a fulcrum associated with the blade-supporting plate for a device to pry up the cap.

15 7. A safety razor having cooperating spring-closed blade-clamping members, one having a projection and the other having a fulcrum shoudered to receive a forked prying device for bearing against said projection to separate the two members.

20 8. A safety razor having cooperating blade-clamping members, one being narrower than the other, a fulcrum projecting from the wider of said members to support a prying device operative to separate said blade-clamping members, and spring means for subjecting the said members to clamping pressure.

25 9. A safety razor having cooperating blade-clamping members, one being narrower than the other and spring pressed toward it, and a fulcrum block having a guideway therein and being pivotally mounted on the wider of said members to facilitate separation of said members against spring pressure.

30 10. A safety razor having cooperating blade-clamping members spring pressed toward each other, one having a longitudinal slot in its outer face, and a fulcrum block pivotally mounted to swing partially in said slot and adapted to facilitate separation of said blade-clamping members.

35 11. A safety razor having cooperating blade-clamping members spring pressed into clamping engagement, one having a longitudinal slot intersected by a cross groove, a fulcrum block having journals located in said cross groove and being arranged to swing partially in said longitudinal slot and adapted to facilitate separation of said blade-clamping members, and a slotted cover plate closing the cross groove.

40 12. A safety razor having cooperating blade-clamping members spring pressed into clamping engagement, a rocking fulcrum block on one of said members having a guideway for a prying device adapted to facilitate separation of said blade-clamping members against spring-pressure, and fixed stops for engaging the prying device to limit its movement about the axis of the fulcrum block.

45 13. A safety razor having cooperating blade-clamping members spring pressed into clamping engagement and one having a fulcrum, in combination with an elongated magazine shaped to engage the fulcrum and movable to pry the blade-clamping members apart to receive a blade from the magazine.

50 14. A safety razor comprising cooperating blade-clamping members spring pressed together and one having an undercut projecting fulcrum, in combination with a forked magazine shaped

to engage said fulcrum and movable to pry the said members apart.

15. A safety razor comprising cooperating blade clamping members spring pressed together and having a fulcrum projecting from one of them, in combination with an elongated blade magazine shaped to engage the fulcrum and to swing into prying engagement with the other member, and stops to limit the swinging movement of the magazine when it reaches blade delivering relation with respect to said blade clamping members.

16. A safety razor comprising cooperating blade-clamping members shaped to receive a blade by endwise horizontal movement between them when the razor is held upright, and a fulcrum projecting from one of said members, in combination with a magazine shaped to engage the fulcrum and to swing into prying engagement with the other member, and stops for arresting the magazine when it has been swung into horizontal position.

17. A safety razor comprising cooperating blade-clamping members shaped to receive a blade by endwise movement between them, and a fulcrum block pivotally mounted on one of said members and having a longitudinal guideway therein, in combination with a magazine having a forked end for engaging in said guideway and being movable first to swing with the fulcrum block into prying engagement with the other clamping member and then to slide longitudinally in the guideway to present a blade in delivering position.

18. A safety razor comprising opposed blade-clamping members having a blade seat between

them shaped to receive a blade by endwise movement, a fulcrum projecting from one member, in combination with a blade magazine having a forked bottom projecting endwise beyond the rest of the magazine and shaped to engage said fulcrum and then slide longitudinally with respect to the fulcrum to facilitate projecting a blade from the magazine in proximity to the blade seat of the razor and to facilitate separation of said blade-clamping members at one end.

19. A safety razor comprising co-operating blade-clamping members loosely connected at one end, and spring means normally pressing said members toward each other throughout their entire length, in combination with a blade magazine having a prying portion for temporarily separating said blade-clamping members at their unconnected ends, and means for projecting a blade between said members while so separated.

20. A safety razor comprising cooperating blade-clamping members loosely connected at one end to prevent complete disengagement and unconnected to permit separation at the other end, a blade-locating rib projecting from one of said members adjacent to its free end, and spring means normally pressing said members toward each other throughout their entire length, in combination with a blade magazine having a prying portion for temporarily separating said blade-clamping members at their unconnected ends, and means for projecting a slotted blade between said members while so separated, the blade being guided in its movement by the said blade-locating rib.
